UNITED STATES PATENT OFFICE.

PAUL WILLER PETERSEN, OF COPENHAGEN, DENMARK.

BRIDGE SCORE-SHEET.

1,284,763.

Specification of Letters Patent. Patented Nov. 12, 1918.

Application filed February 14, 1917. Serial No. 148,689.

To all whom it may concern:

Be it known that I, PAUL W. PETERSEN, a subject of the King of Denmark, residing at Copenhagen, Denmark, have invented certain new and useful Improvements in Bridge Score-Sheets, of which the following is a full, clear, and exact description.

This invention relates to score or tally sheets for auction bridge and has for its object the provision of an article of this character which is of a size to be conveniently handled, provides sufficient space for keeping score of a large number of games and "rubbers", and is so arranged that the scores of the games, "rubbers" and the individual scores of the players, may be easily recorded and will be in open view for examination by the players. The invention will be described in connection with the accompanying drawings, and will be particularly pointed out in the appended claim.

In the drawings:

Figure 1 shows a sheet which is adapted to be folded to form the score-card;

Fig. 2 shows the first division or leaf of the card which is utilized;

Fig. 3 shows the second division; and

Fig. 4 shows the third division of the card when folded.

As will be clear from Fig. 1, the score card comprises a rectangular sheet of paper which is of greater width than length, which is ruled by a heavy line 1 to provide at the top of the sheet a horizontal space which extends the entire width of the sheet. This space may be ruled horizontally to provide four horizontal columns 2, 3, 4 and 5. This space may also be ruled vertically by a line 6 to provide a vertical column at the upper left-hand corner of the sheet. The remainder of the sheet is ruled into vertical columns by heavy vertical lines 7, which columns are again sub-divided by light lines 8. In the form shown, the heavy vertical lines divide the space into nine columns which will give sufficient space to keep the score of the nine rubbers, as will be later described. A horizontal line 10 divides each of the vertical columns into two substantially equal divisions, the upper division being utilized to record the "honors" and the lower division for the "points", as is the

customary practice in keeping a bridge score.

The top portion of the sheet is cutaway as at 11, which cutaway portion is preferably of a length and width corresponding to the length and width of the vertical column located to the left of the line 6. This cutaway portion is positioned above the third vertical column from the right-hand edge of the paper, the purpose of which will be later referred to. The horizontal columns 2, 3, 4 and 5 above the heavy horizontal line 1 may be also ruled vertically by lines 12, if desired, to provide a number of vertical columns above the horizontal line 1 equal to the number of columns below line 1.

The sheet described is folded up along two of the vertical lines 7 to provide three equal divisions or leaves and is used as a score card in its folded form when it is of a size to be conveniently handled. Moreover since a plurality of thicknesses of paper are thus provided, the card even though made of paper, will have sufficient body to prevent a pencil from cutting the paper if it is marked upon when supported by a soft backing, such as a baize-covered table.

The advantages of the card will be apparent from a description of the manner in which it is used to keep score for auction bridge.

Before starting, the names of the players are written in the vertical column provided in the upper left-hand corner of the sheet to the left of the line 6, and we will, for convenience, enumerate the players as A, B, C and D. If we assume that A and B, and C and D are playing as partners, as is the usual custom, the score keeper utilizes the left-hand vertical column for keeping the score of the first rubber, one-half of this vertical column being utilized for one pair of partners and the other half for the other pair of partners. Assuming that A is keeping score, he will then write at the top of these two columns the words "we" and "they" or equivalent words, as is the usual practice, "we," of course, meaning A and B, who are the playing partners, and "they" C and D who are the opposing partners. Assuming that the first rubber has been played, the honors being marked above the horizontal

line and the points below the horizontal line, and that C and D win the rubber by making 437 points. The score keeper then records this score in the horizontal columns opposite each player's name; *i. e.* by giving to A and B, who have lost, a score of minus 437, and to C and D a score of plus 437. The second rubber is played in the same manner, except this time A and C are the playing partners, 10 and B and D the opposing partners. Assuming that A and C win the rubber with a score of 601 points. This will give A, who previously was minus 437, plus 164, and this score is placed in the A's horizontal column. 15 The score of B, which was previously minus 437, will now be minus 1038, and this is marked in B's column. C, who has won both games, will have a total score of 1038 which is marked in his column, and D, who has 20 won the first game and lost the second, will have a score of minus 164. The third rubber is played in the same way, A and D, and B and C playing as partners, and assuming that A and D win the game by 608 points, 25 the total individual score of A for the three rubbers will be plus 164, and plus 608, or plus 772, which will be placed in A's horizontal column. B has again lost, and his total score will be a minus 1038, plus a minus 30 608, or a total of a minus 1646, which is placed in his column. The total scores of C and D are placed in their respective horizontal columns in the same manner. The first leaf or 35 division of the score card is then entirely used up and the card is then turned over and the middle division of the card utilized. On the fourth rubber, assuming that A and B, and C and D are again playing as partners, and A and B win the rubber with a score of 40 407 points. The individual scores of the players are then tallied as before. As will be clear, to do this, the card must be turned over to find out A's total score at the end of the third rubber, and the score keeper will, 45 when determining this score, also determine in which column A's score belongs. That is, when he looks at the back of the card to read A's previous score, which was 772 and mentally adds to this 407, he also determines in 50 which horizontal column to place A's score. In the same manner, the individual scores of each of the other players is determined and written down in their respective horizontal columns, and this manner of keeping 55 score is continued through the fifth and sixth rubbers when the second leaf of the sheet will be entirely filled. If, at any time, the score keeper is in doubt as to which of the horizontal columns the individual scores of 60 the respective players belong, he can readily determine this by merely looking at the back of the card which contains the previous scores of the players from the beginning.

After the sixth rubber has been finished, 65 the card is then taken and the first leaf of

the card folded so that it is within instead of outside the third division of the card. This will bring the cut-out portion of the card opposite the left-hand vertical column in which the names of the players are written so that these names need not be re-written. The seventh, eighth and ninth rubbers are then played and the scores kept in the manner previously described. In playing the seventh rubber, let us assume 75 that A and B are playing partners and have won the rubber by a total score of 526. To determine A's individual score for the sixth rubber so that the score for the seventh rubber may be added thereto, it is merely 80 necessary to look at the back of the card and add it to his score for the sixth rubber, as, for example, by looking at the back of the card the score keeper determines that A's individual score for the sixth rubber is 85 minus 443 and when plus 526 is added to it, the total score of A will be plus 83, which will be placed in the horizontal column opposite A's name or initial, which now appears through the cut-out portion. The individual score of B, C and D may also be recorded in their horizontal columns in the same manner, and the eighth and ninth rubbers played as before when the sheet will be entirely used up, the total individual 95 scores for the nine rubbers appearing in the horizontal columns opposite each of the player's names.

It should be noted that when the individual scores of the players are added up at 100 the end of each rubber, the plus and minus will balance, which will give a convenient check to the score-keeper and prevent him from making errors in the score. It will also be seen that once the sheet is folded it 105 is unnecessary thereafter to unfold it for the score keeper or any player to determine what the individual scores of each of the players were at the end of the last rubber, 110 since this question can always be determined merely by looking at the card or at the back if the card has just been turned and a new leaf is being used.

If desired, holes 13 may be punched in the sheet adjacent its lower edge, which holes come into alignment when the sheet is folded. The score keeper may push his pencil or pen through these holes and the pencil or pen will thus be retained in place until it is required for recording the next score. To 120 prevent the pencil from splitting the holes open, the paper may be split for a short distance above the holes as at 14.

I claim:

A bridge score comprising a rectangular sheet of paper having a horizontal space at the top extending the entire width of the sheet, said space being of sufficient depth to permit the names of the individual players to be placed one under the other and their 130

individual scores upon a horizontal line after their respective names, the remainder of the sheet being ruled to provide a plurality of vertical columns for recording the 5 honors and points of each rubber, said sheet being folded in three equal leaves along the division lines between the vertical columns, and utilized in folded condition as a score

card, the third leaf having a cut-out portion in its upper edge at the top of the first 10 vertical column thereon of a size, shape and location to appear opposite the space to be occupied by the names of the players.

In witness whereof I subscribe my signature.

PAUL WILLER PETERSEN.
